UNITED STATES PATENT OFFICE.

PRINCE A. POTTER, OF PROVIDENCE, RHODE ISLAND.

BARREL-SWING.

SPECIFICATION forming part of Letters Patent No. 310,539, dated January 6, 1885.

Application filed November 17, 1884. (No model.)

To all whom it may concern:

Be it known that I, PRINCE A. POTTER, a citizen of the United States, residing at Providence, in the county of Providence and State 5 of Rhode Island, have invented new and useful Improvements in Barrel-Swings, of which the following is a specification.

My invention relates to that class of devices commonly known as "barrel-swings," designed for the use of grocers, housekeepers, and others to facilitate the removal and replacement of barrels stored beneath counters and elsewhere.

It is the purpose of my invention to provide 15 a barrel-swing which may be quickly, easily, and securely attached to and as readily detached from barrels of different sizes without the use of nails or similar fastenings, and which forms, during the time the barrel is in use, a 20 permanent attachment thereto.

It is also the purpose of my invention to provide a turn-spindle which is adapted to operate in combination with the swing, the parts being so constructed and connected that dust 25 or other refuse matter will not collect in the spindle-pocket and increase the friction of the bearings.

My invention consists in the several novel features of construction and combinations of 30 parts, hereinafter fully set forth, and definitely pointed out in the claims.

Referring to the drawings forming part of this application, Figure 1 is a plan view of a barrel end, showing my invention attached. 35 Fig. 2 is a vertical section of the swing with the turn-spindle combined.

In the said drawings, the reference-numeral 1 denotes the bar within which the rolls are supported. This bar may be of any suitable 40 form, either curved or straight, though I have shown it as composed of two similarly-curved portions united at or about the center of the bar 1. In the outer ends of the latter, rolls 2 are journaled between ears or lugs 3, the axis 45 of each roll being in a line drawn radially from a common center.

From the central portion of the bar 1 projects a straight bar, 4, having one of its vertical sides or edges serrated or roughened to give 50 increased frictional contact. This bar engages with a bar, 5, the adjacent face of which is also serrated, said bar being provided with a loop,

6, which receives the bar 4, and also a key or wedge, 7, bearing upon the outer side of the bar 4.

Upon the free end of the bar 5 is formed a T-head, 8, having spurs 8^a, projecting outwardly therefrom, similar spurs, 9, being formed upon the ends of the roll-carrying bar 1, and upon the upper surfaces of the bar 1, near its center, is formed a sharp nipple or point, 9^a, projecting upward, the purpose thereof being shown hereinafter.

At or near the central point of the head 8 is formed a socket, 10, which receives the end of 65 a spindle, 11, having a flange, 12, which is firmly secured to the floor by screws.

The manner of applying the swing is as follows: The barrel being placed upon its bilge, the parts composing the swing are connected 70 loosely by inserting the bar 4 within the loop 6 and placed upon the barrel end within the chines, with the spurs 9 bearing thereon. The portion carrying the rolls is then raised and dropped with some force upon the chine, driving the spurs therein or under the strips generally found on all barrels, after which the bar 4 is brought up against the head, forcing the spur 9^a into the wood and preventing the spurs 9 from withdrawing. The other part is then 75 attached in a similar manner by dropping it upon the opposite chine until the spurs 8^a enter the wood, when the key 7 is driven up, fastening the parts securely in place. The barrel is then placed on its end and the socket 10 is 80 set upon the spindle 11.

It will readily be seen that this swing may be easily applied to barrels of any size without using nails, staples, or any similar fastenings. The spindle 11 projecting upward from 90 the floor and the spindle-socket opening downward, no dirt or other foreign matter is collected thereby. In other devices of this class the spindle has been set in a step upon the floor, which constantly collects dirt, creating 95 great friction upon the spindle, obstructing its operation, and rapidly wearing it away.

What I claim is—

1. A barrel-swing composed of two parts adjustable one upon the other, one of said parts carrying the rolls, and the other the spindle-socket, each part having spurs which engage with the chine at opposite points upon the barrel end, substantially as described.

2. In a barrel-swing, the combination, with a bar having rolls journaled in its ends and provided with outwardly-projecting spurs, of a central bar engaging with a loop formed upon 5 a separate piece having a spurred T-head, and a wedge or key entering said loop, substantially as described.
3. In a barrel-swing, the combination, with a spurred roller-carrying bar having a point 10 projecting upwardly near its middle part, of an adjustable bar having a spurred end, and a wedge or key by which the parts are fastened at any point to which they are adjusted, substantially as described.
- 15 4. In a barrel-swing, the combination, with a roller-carrying bar having spurs near its ends, and a point or nipple projecting upward near its middle, of a bar formed centrally thereon, a bar having a spurred T-head, and provided with a spindle-socket, a loop formed upon 20 said bar, and a key entering said loop and bearing upon the central bar of the roll-carrier, substantially as described.
5. In a barrel-swing, the combination, with a bar, 1, having rolls 2, and provided with 25 spurs 9^a, of the bar 4, entering the loop 6 upon the bar 5, the T-head 8, having spurs 8^a, and the key 7, substantially as described.
6. In a barrel-swing, the combination, with the spurred bar 1, having rolls 2, and provided 30 with the point or nipple 9^a, of the bar 5, having the loop 6, the T-head 8, having the spurs 8^a, and spindle-socket 10, and the key 7, substantially as described.
7. In a barrel-swing, the combination, with 35 the spurred bar 1, having rolls 2, and provided with a central bar, 4, of the bar 5, having the loop 6, the key 7, the T-head 8, having a spindle-socket, 10, and the spindle 11, substantially as described.

In testimony whereof I affix my signature in presence of two witnesses.

PRINCE A. POTTER.
